UNITED STATES PATENT OFFICE

DAVID LEWIS, OF NEW YORK, N. Y., ASSIGNOR TO NAT LEWIS WHOLESALE CORPORATION, OF NEW YORK, N. Y., A CORPORATION OF NEW YORK

DESIGN FOR A LADY'S HAND BAG

Application filed February 20, 1931. Serial No. 38,744. Term of patent 3½ years.

To all whom it may concern:

Be it known that I, DAVID LEWIS, a citizen of the United States, and a resident of New York city, county and State of New York, have invented a new, original, and ornamental Design for a Lady's Hand Bag, of which the following is a specification, reference being had to the accompanying drawings, forming a part thereof.

Fig. 1 is a front view of the hand bag; Fig. 2 is a perspective view of the hand bag; and Fig. 3 is a view of the hand bag with the flap open.

I claim:

The ornamental design for a lady's hand bag as shown.

Dated, February 19th, 1931.

DAVID LEWIS.
